UNITED STATES PATENT OFFICE.

GEORGE E. RIBLET, OF ERIE, PENNSYLVANIA.

CARBURETOR.

Application filed April 13, 1922. Serial No. 552,080.

To all whom it may concern:

Be it known that I, GEORGE E. RIBLET, a citizen of the United States, residing at Erie, in the county of Erie and State of Pennsylvania, have invented new and useful Improvements in Carburetors, of which the following is a specification.

This invention is designed in a simple and efficient manner to control the introduction of air and fuel and to provide a simple and efficient means for adjusting the same.

The invention is illustrated in the accompanying drawings as follows:—

Fig. 1 shows a side elevation of the carburetor.

Fig. 2 a section on the line 2—2 in Fig. 1.

Fig. 3 a section on the line 3—3 in Fig. 1.

Fig. 4 a side elevation of the air valve.

Fig. 5 a side elevation of the air valve in a direction at right angles to that shown in Fig. 4.

Fig. 6 an outline view of an engine and carburetor attachment.

Fig. 7 a sectional view of an alternative structure.

Fig. 8 a side elevation of the air valve in the alternative construction.

A marks the engine, B the manifold and C the intake leading from the carburetor to the manifold, the intake having a flange D to which the carburetor is attached.

1 marks the carburetor body. This is provided with a flange 1^a for securing to the flange D. The body is provided with an annular air passage 2 leading from an air inlet passage 3, the passage 3 being controlled by a gate valve 4, the gate valve having an adjusting stem 5 extending through the walls of the passage and being provided with an adjusting nut 6. A spring 7 tends to hold the gate valve in adjusted open position.

The suction passage has the usual restriction 8 and terminates with a cylindrical portion 9 at its lower end. An air valve 10 is cylindrically shaped and moves axially into and out of the cylindrical portion 9. It is mounted in an opening 11 in axial alignment with the restriction. Valve operating stems 12 extend radially from the valve through cam openings 13 in the walls of the body. An operating rod 12^a extends to the dash (not shown). The valve as shown in Fig. 2 is about mid-position.

A metering pin stem 14 has a passage 15 through it and is mounted in an opening 16 in the air valve. The passage 15 leads to an

annular chamber 17 through radial openings 18. The metering pin 18^a extends from the top of the stem to a point above the valve forming an annular nozzle slot 19, the inner wall of this slot formed by the metering pin extending above the outer wall. The opening 16 extending downwardly with a cylindrical wall from the slot 19 makes the taper of the passage leading to the slot very abrupt, the taper of the metering pin receding from the walls of the opening immediately below the slot.

A sleeve 20 has an internal screw thread 21 which screws on to a screw thread 21^a on the stem. This sleeve has external screw threads 22 which screw into the threads 23 in the body. A lever 24 is secured to the sleeve 20 and a rod 24^a extends from this to the dash (not shown). This gives to the metering pin the initial adjustment as desired. The external threads on the sleeve 20 should have a reverse pitch from those on the inside of the sleeve, that is to say, one should be right and the other left so that a double action is given to the stem with a given movement of the lever. A union member 25 is screwed on to the lower end of the stem. A second member of the union 26 cooperates with the member 25 securing the supply pipe 27 within the union and in communication with the passage 15. In order to give the metering pin its initial adjustment the union is loosened and the pin turned to the position desired. It is then locked in this position by a lock nut 28.

In order that the air delivered for idling may be more accurately controlled I prefer to incline the meeting faces of the restriction 8 and upper end of the valve. As shown these are inclined in both directions, in other words, fluted. As the air valve moves downwardly from the cylindrical part 9 openings are formed at the lower part of the inclinations and these gradually widen and increase as the air valve is lowered. This permits of a very accurate adjustment of the air valve for idling. Further inasmuch as the movement of the air valve is accompanied by a corresponding movement of the metering pin this reduces the speed at which the air passage is opened relatively to the opening of the metering pin and this is desired in the idling condition. A stop screw 13^a is provided operating at the end of the cam slot 13 determining the point to

which the air valve may be closed for idling.

In the alternative construction I have provided a movable restriction or venturi 30. This is screw-threaded into a ring 31 in the body. These form two restrictions, one at 32 between the throat of the venturi and the metering pin and the other 33 between the ring 31 and the upper part of the valve. When the venturi is moved upwardly it increases the opening at 32 and consequently makes the restriction at 33 the more controlling. Where the greater restriction is opposite the metering pin there is a less pull on the gasoline than where the greater restriction is in the opening 33.

What I claim as new is:—

1. In a carburetor, the combination of a body having a suction passage; an air valve in axial alinement with the passage; means 20 for moving the air valve axially to vary the air opening; a fuel passage in the air valve

terminating in a nozzle; and a metering pin in the nozzle varying the opening as the air valve moves, said metering pin extending through the valve and forming a fuel connection to the fuel passage.

2: In a carburetor, the combination of a body having a suction passage; an air valve in axial alinement with the passage; means for moving the air valve axially to vary the air opening; a fuel passage in the air valve terminating in a nozzle; a metering pin in the nozzle varying the opening as the air valve moves; and means for adjusting the metering pin comprising a sleeve externally 35 screw-threaded and screwed into the body and internally screw-threaded and screwed on to the pin.

In testimony whereof I have hereunto set my hand.

GEORGE E. RIBLET.
